(57) **CLAIM**

The ornamental design for a cradle interface pad as shown and described.

DESCRIPTION

FIG. 1 is a front-left perspective view of a cradle interface pad according to a first embodiment of the claimed design. FIG. 2 is a rear-left perspective view of the cradle interface pad of FIG. 1.

FIG. 3 is a top view of the cradle interface pad of FIG. 1. FIG. 4 is a bottom view of the cradle interface pad of FIG. 1.

FIG. 5 is a rear view of the cradle interface pad of FIG. 1. FIG. 6 is a front view of the cradle interface pad of FIG. 1. FIG. 7 is a right side view of the cradle interface pad of FIG. 1.

FIG. 8 is a left side view of the cradle interface pad of FIG. 1.

FIG. 9 is a sectional view of the cradle interface pad of FIG. 1 taken along line 9-9 in FIG. 3.

FIG. 10 is a front-left perspective view of a cradle interface pad according to a second embodiment of the claimed design.

FIG. 11 is a rear-left perspective view of the cradle interface pad of FIG. 10.

FIG. 12 is a top view of the cradle interface pad of FIG. 10. FIG. 13 is a bottom view of the cradle interface pad FIG. 10. FIG. 14 is a rear view of the cradle interface pad of FIG. 10. FIG. 15 is a front view of the cradle interface pad of FIG. 10. FIG. 16 is a right side view of the cradle interface pad of FIG. 10.

FIG. 17 is a left side view of the cradle interface pad of FIG. 10; and,

FIG. 18 is a sectional view of the cradle interface pad of FIG. 10 taken along line 18-18 in FIG. 12.

(Continued)

The dash-dot sectional broken lines in FIGS. 3 and 12 of the drawings form no part of the claimed design.
The broken lines in the drawings illustrate portions of the cradle interface pad that form no part of the claimed design.

1 Claim, 18 Drawing Sheets
